UNITED STATES PATENT OFFICE.

RUSSELL RICHARD SUPPLEE, OF BRIDGEPORT, PENNSYLVANIA.

AUTOMATIC SAFETY ANGLE COCK.

Application filed October 23, 1926. Serial No. 143,733.

This invention relates to improvements in the angle cock commonly used in air brake systems, these angle cocks being disposed at the ends of the train pipe carried by the car or engine, air being maintained at a predetermined pressure within this train pipe to thereby automatically apply the brakes by reduction of train line pressure.

The general object of the present invention is to provide means which will lock the valve of the angle cock in open position when train pressure is maintained at standard or is within twenty points of the standard train pressure, the angle cock becoming unlocked when the train pressure is reduced for the purpose of applying the brakes.

Another object is to provide an angle cock of this character which if closed after the engineer or other operator has made a reduction in the train pipe pressure will make a still further reduction in train pipe pressure and, therefore, act as a signal giving warning to the engineer or operator by setting the brakes much tighter than ordinarily.

Still another object is to provide an angle cock which cannot be shut off so long as standard pressure is maintained in the train pipe.

A further object is to provide an angle cock which will drain the surplus air out of the hose forming part of the flexible joint connecting car to car, thus removing the danger to trainmen present where the service pressure has not been drained out and a train is divided.

A still further object is to provide a valve of this character which is adapted to be used not only for air but for steam or liquid where these fluids are used in braking devices.

My invention is illustrated in the accompanying drawings wherein:—

Figure 1 is a longitudinal sectional view of my improved angle cock;

Fig. 2 is a section on the line 2—2 of Figure 1;

Fig. 3 is an under side plan view of the angle cock.

Referring to these drawings it will be seen that the body 10 of the angle cock has the ordinary shape of the standard angle cock, one end being interiorly screw-threaded at 11, the other end being downwardly extended as at 12, and the body having a longitudinally extending bore 13. Intersecting

this bore is the usual rotatable tapered valve 14 which extends up through the body to the upper face thereof. The stem of this valve carries upon it the generally circular disk 15 formed at one point in its circumference with the notch 16 and at the opposite point with a shoulder 17, from the base of which extends a flat face 18 which extends chordally with relation to the circumference of the disk.

The top of the body is formed with a circular chamber 19, within which this disk 15 is disposed, this chamber being interiorly screw-threaded for the reception of the plug 20. A spring 21 is disposed between this plug and the valve and urges the valve downward. The lower end of the valve is provided with a stem 22 upon which the handle 23 is attached, this handle having a lug 24. The body on its under face is formed with the hub 25 having two shoulders 26 and 27 disposed at an angle of 90° with relation to each other and against which the lug 24 is adapted to engage in the two positions of the valve. It will be understood, of course, that the disk 15 rotates with the valve 14.

The valve body is provided on one side of the disk with a longitudinally extending chamber 28 having a lining 29 and disposed within this chamber is the piston head 30 operating against the lining and having the longitudinally extending skirt 31 and carrying a stem 32. This stem 32 passes loosely through the piston and is provided at one end with a nut 33 and inward of this end with a shoulder 34, which bears against the shoulder at the inner extremity of the skirt. When the nut 33 is tightened up, the shoulder will be clamped against the piston head, and the stem and piston will move as one. The end of chamber 28 is closed by a plug 35 having the recess 36 to accommodate the nut 33. The piston rod or stem 32 of piston 30 constitutes a pin extending through a bore 37 which communicates with the chamber 19, and this stem, when the angle cock valve 14 is open, extends into the recess 16 and locks the valve from rotative movement.

It will be noted from Figure 1 that the plug 35 is formed with a partially arcuate recess 38 and a port 39 extends from the adjacent end of the bore 13 into this recess 38. Thus, the recess 38 will have in it the same pressure as will the entrance end of the angle cock.

2
The body on the opposite side of the disk 15 from chamber 28 is formed with a valve chamber 40 having a lining 41 formed to provide a valve seat 42. Resting against this valve seat is a valve 43 having a stem 44 which extends through a bore 45 in the inner wall of the chamber and, when the valve 14 is in its open position, engages against the shoulder 17, as shown in Figure 2.

10 The outer end of the chamber 40 is closed by a plug 46 and a spring 47 urges the valve 43 to its seat. The valve chamber is provided with a vent 48 between the seat 42 and the bore for stem 44 and the interior of 15 the valve chamber is connected to the outlet end of the angle cock bore by means of the duct 49.

The operation of this mechanism is as follows:—In running position with standard 20 pressure or normal pressure within the train pipe, the pressure on the piston head 30 will force the piston 30 to the left in Figure 1 against the action of the spring and the pin 32 will be forced into engagement with 25 the notch 16, thus locking the valve against any rotation. Whenever the train pipe pressure is raised to within twenty pounds of the standard or normal train pipe pressure, the piston 30 will move forward and 30 carry the pin 32 into its locking position, thus locking the angle cock. Whenever a service reduction is made in order to apply the brakes or when the train pipe is free of air, the piston 30 will be urged outward 35 by the spring, thus withdrawing the pin 32 from the disk 15 and thus unlocking the rotary valve 14. The angle cock can then be opened or closed by means of the handle 23. In order to close the angle cock, therefore, as would be necessary for instance, in 40 dividing the train or cutting out cars, it is necessary for the engineer or operator to make a normal train pipe reduction of twenty pounds, which will unlock the disk and 45 permit the valve 14 to be rotated by hand.

If after the engineer makes a reduction in the train pipe which unlocks the valve, a person either maliciously or accidentally should attempt to close the angle cock, this 50 action would cause the face 18 to cam against the valve stem 44, opening the valve 43, permitting the escape of air through duct 49 and vent 48 and this would cause a heavier reduction of pressure, setting the 55 brakes tighter and acting as a warning to the engineer or trainman.

When dividing a train, the engineer will 60 make a train pipe reduction, then both adjacent angle cocks can be closed off. This will act to open the angle cock vent valves 43 of adjacent train pipe couplings and these valves will drain the surplus air out of the hose or universal joint coupling between the train pipes, removing the present danger to 65 trainmen in uncoupling the hose or universal valve having a pin extending through the

joint when the pressure is on. By thus using this automatic angle cock in dividing a train and leaving one part of the train on a grade, the brakes on this part of the train so left would be applied and the train could 70 not run or drift away.

It is to be understood that I have described in the present instance but one embodiment of my invention. In practice certain modifications and changes may be made 75 in the detailed construction and arrangement of parts in order to adapt the invention to different systems or to enable the improved angle cocks to be used in accordance with the circumstances of any particular case.

I claim:—

1. In an angle cock, a rotatable valve, means acting to automatically lock the valve in its open position when pressure within the train line is increased beyond a predetermined point and acting to unlock said valve when pressure is decreased beyond a predetermined point, the opposite end of the angle cock body being provided with a vent, a chamber into which the vent opens, a valve in the chamber normally closing the vent and resiliently urged to a seated position, said valve having a pin extending through the wall of the chamber, the valve being formed to provide a member rotatable with the valve and having a shoulder in its periphery, and a face extending outward from the base of said shoulder to the circumference of the disk, said shoulder being so located that when the valve is open, said pin may seat within the recess bounded by the shoulder and face, the face acting as the valve is rotated to open position to bear against the pin and open the vent valve. 105

2. In an angle cock, a body, a rotatable valve therein having a handle, the valve at its upper end being provided with a disk formed with a notch at one point and at a diametrically opposite point with a recess bounded by a radial shoulder and a face extending out toward the periphery of the disk, the body at one end being provided with a longitudinally extending chamber communicating at its outer end with the interior of the body, a piston movable in the chamber, a spring urging the piston outward, a pin carried by the piston and extending through the inner end wall of the chamber and adapted to engage in the notch in the disk when the rotary valve is turned to open position, the opposite end of the body being provided with a valve chamber, the interior of the valve chamber being connected by a duct with the interior of the body, and the valve chamber having a vent at the inner end of the chamber, a valve within the chamber, a spring urging the valve to a position to close said vent, the valve having a pin extending through the 125

end of the chamber and into said recess in the disk when the rotary valve is turned to an open position.

3. In a fluid braking apparatus, an angle cock, a rotatable valve therein, a member carried by said valve and rotatable therewith and having a notch on one face and being formed in its periphery with a shoulder and a face extending outward from the base of said shoulder to the circumference of the member, the body of the angle cock being formed with a longitudinally extending chamber connected at its outer end to the interior of the inlet end of the angle cock, a piston operating in said chamber, a spring urging the piston outward, the piston carrying a locking pin engageable with the notch in said member when the rotatable valve is opened and pressure raised in the train line, said spring acting to urge the piston in a direction to carry the pin out of locking engagement with the member when the train line pressure is reduced, the body of the angle cock being provided with a vent, a valve normally closing the vent and resiliently urged to a seating position and having a pin extending into contact with the periph-

ery of the member, said pin coacting with said shoulder and said shoulder being so located that when the valve is opened the 30 pin may seat within the recess bounded by the shoulder and face, the face acting as the valve is rotated to open position to bear against the pin and open the vent valve.

4. In an angle cock, a rotatable main valve 35 therein, a member rotating with the valve, means coacting with said member to lock the valve in its open position when the pressure within the train line is increased beyond a predetermined point and acting to 40 unlock said valve when the pressure is decreased beyond a predetermined point, a valve formed in the body of the angle cock and communicating with the interior of the body, and a vent valve normally closing said 45 vent and urged to a closed position, said member acting as the valve is rotated to open position to open the vent valve and when the rotatable valve is rotated to a closed position to permit the vent valve to 50 close.

In testimony whereof I hereunto affix my signature.

RUSSELL RICHARD SUPPLEE.
